DISPENSING CONTAINER FOR POWDERED PRODUCTS OR THE LIKE

Harold J. Vanderhyde, North Merrick, N.Y., assignor to
The Procter & Gamble Company, Cincinnati, Ohio, a corporation of Ohio

Filed June 12, 1967, Ser. No. 7,426

Term of patent 14 years

(Cl. D9—44)

Fig. 1

Fig. 2

Fig. 3

Fig. 5

FIG. 1 is a front elevational view of a dispensing container for powdered products or the like showing my new design.

FIG. 2 is a side elevational view of the same as seen from the right of FIG. 1.

FIG. 3 is a side elevational view of the same as seen from the left of FIG. 1.

FIG. 4 is a top plan view of the same; and

FIG. 5 is a cross sectional view of the same, taken on the line 5—5 of FIG. 1.

The side not shown is the mirror image of the side shown.

I claim:

The ornamental design for a dispensing container for powdered products or the like, as shown and described.
